(57) **CLAIM**

The ornamental design for a device for holding portable electronics, as shown and described.

DESCRIPTION

FIG. 1 is a perspective view according to an embodiment of a device for holding portable electronics; FIG. 2 is a front elevation view thereof; FIG. 3 is a right side elevation view thereof, the left side elevation view being mirror-symmetrical thereto; FIG. 4 is a rear elevation view thereof; FIG. 5 is a top plan view thereof; FIG. 6 is a bottom plan view thereof; and, FIG. 7 is a perspective view thereof, showing an exemplary portable electronic device held therein.

The broken lines represent unclaimed features of the claimed design. The unshaded surfaces bounded by broken lines form no part of the claimed design. The long dash, double dash lines represent surface boundaries of the claimed design.

1 Claim, 7 Drawing Sheets
